[57] CLAIM

The ornamental design for an anal protective liner, as shown.

DESCRIPTION

FIG. 1 is a bottom perspective view of an anal protective liner, showing my new design;

FIG. 2 is a bottom plan view thereof;

FIG. 3 is a left end elevational view thereof;

FIG. 4 is a right end elevational view thereof;

FIG. 5 is a side elevational view thereof; the opposite side elevational view being identical thereto; and,

FIG. 6 is a top plan view thereof.
